(57) **CLAIM**

The ornamental design for a coffee roaster, as shown and described.

DESCRIPTION

FIG. 1 is a front, right side, top perspective view of the coffee roaster showing my new design;
 FIG. 2 is a rear, left side, bottom perspective view thereof;
 FIG. 3 is a front elevational view thereof;
 FIG. 4 is a rear elevational view thereof;
 FIG. 5 is a left side elevational view thereof;
 FIG. 6 is a right side elevational view thereof;
 FIG. 7 is a top plan view thereof; and,
 FIG. 8 is a bottom plan view thereof.

The broken lines immediately adjacent to the claimed portions are boundaries, all other broken lines are environmental structures; all the broken lines form no part of the claimed design.
